H. NETTGENS.
BURNER FOR GASEOUS AND LIQUID FUELS.
APPLICATION FILED FEB. 3, 1922.

1,415,383.

Patented May 9, 1922.

Inventor:

Heinrich Nettgens.

UNITED STATES PATENT OFFICE.

HEINRICH NETTGENS, OF ALBISRIEDEN, NEAR ZURICH, SWITZERLAND, ASSIGNOR
TO EDUARD STRAUB-KELLER, OF SULGEN, SWITZERLAND.

BURNER FOR GASEOUS AND LIQUID FUELS.

1,415,383.

Specification of Letters Patent.

Patented May 9, 1922.

Application filed February 3, 1922. Serial No. 533,811.

To all whom it may concern:

Be it known that HEINRICH NETTGENS, a citizen of the Republic of Switzerland, residing at Albisrieden, near Zurich, Switzerland, has invented certain new and useful Improvements in Burners for Gaseous and Liquid Fuels, (for which I have filed application in Switzerland Dec. 3, 1920, No. G 9,675; Germany July 12, 1921, No. N 20,123,) of which the following is a specification, reference being had therein to the accompanying drawing.

The object of the present invention is a burner for gaseous and liquid fuels. The burner comprises a nozzle having a bore for the passage of air in the first case, i. e. when used for burning gaseous fuels, and of oil in the second case, i. e. when used for burning oil or liquid fuels, the amount of the medium passing through said bore being controlled by means of a regulating device. Further an adjustable nozzle is provided forming in conjunction with the first mentioned nozzle an opening that can be adjusted or closed by means of the adjustable nozzle and which forms the continuation of a channel adapted to guide the gas in the first case and the air in the second case. As both supply passages are controlled by regulating means, a determined quantity of air that is necessary for the combustion can be supplied to the fuel, the amount of which is chosen with regard to the temperature desired, whereby any excess of air is avoided. Moreover the burner is so designed that a better mixture of the medium is effected than in the case with the hitherto known burners whereby in conjunction with the possibility of regulating of the two supply passages a perfect combustion results.

The object of the present invention is illustrated by way of example in the accompanying drawings, in which:

Fig. 1 is a side elevation,

Fig. 2 is a vertical longitudinal section along line II—II of Fig. 1, and

Fig. 3 is a section along line III—III of Fig. 1.

The illustrated burner comprises a main body 1 having a centrally situated nozzle 2, the bore 3 of which terminates in a funnel-shaped enlargement 4 adjoining to a contracted portion. 5 denotes an annular channel to which a supply branch 6 joins. At its

front end the wall of the nozzle 2 serves in 55 cooperation with the adjustable nozzle 7 to form an annular channel 8 (Fig. 2) which is controlled by the adjustable nozzle 7; in Fig. 2 the channel 8 is shown closed. The adjustable nozzle 7 is slidably mounted upon 60 the body 1 of the burner and is in operative connection by means of two arms 9 with a hand wheel 10. The arms 9 are slidably fitted to the body 1 by the set screws 11, and the hand wheel 10 is rotatably mounted upon 65 a screw threaded spindle 12 fixed to the body 1. 13 denotes a stuffing box interposed between the parts 1 and 7. As will be seen in Fig. 2 the supply branch 6 and the annular channel 5 are in connection with the bore 3 70 of the nozzle 2 by means of bore 14 provided near the rear end of the bore 3. 15 denotes a supply branch leading to the bore 3 of the nozzle 2 by means of a supply channel 16, controlled by a valve 17 and arranged so as 75 to cause a zig-zag-shaped course for the medium passing through said channel.

The burner with its various parts in the position shown in Figs. 2 and 3 is ready for burning a liquid fuel, for instance oil. The 80 branch 6 is thereby intended for the supply of air and the branch 15 for the supply of oil. At first air is caused to pass through the branch 6 in the direction of the arrow indicated into the channel 5 whereby part of 85 the air flows through the channel 14 into the bore 3. Then the valve 17 controlling the oil supply is opened. The incoming oil is projected at right angles to the air current in the bore 3 whereby an efficient mixture 90 between the oil and the air occurs thus effecting a good vaporizing of the oil already within the nozzle 2. By a suitable displacement of the adjustable nozzle 7 effected by turning the hand wheel 10 the annular channel 8 is opened. The mixture leaving the nozzle 2 at its front end is now whirled round by the air issuing from the annular channel 8 as this air impinges upon the fuel-air mixture leaving the nozzle 2 in a direction that is different to the direction of the flow of the mixture, thereby the vaporization of the oil and a good mixture of the latter with the air for combustion is caused. The valve 17 permits the adjustment of the oil 100 supply in order to attain a desired temperature and by means of the adjustable nozzle 7 the supply of air can be so regulated that

neither too little air nor an excess of air is admitted, so that a perfect smokeless combustion takes place.

If the above described burner is intended 5 to be supplied with a gaseous fluid instead of with oil, the channel 14, which is tapped, is closed by means of a long screw which is screwed into the body 1 replacing the screw 18 (Fig. 2). In this case the air is admitted 10 to the bore 3 through the branch 15 and the channel 16 while the gas is supplied through the branch 6, the bore of which is larger than that of the branch 15, and through the annular channel 5. By means of the adjustable nozzle 7 and the valve 17 the quantity 15 of the fuel and of the air can be so regulated that the desired temperature is attained and that a perfect smokeless combustion takes place.

20 I claim:

1. A burner for gaseous and liquid fuels, having in combination a nozzle with a bore that is funnel-shaped at one end and adapted for the passage of a medium constituting an 25 element of a combustible, a regulating device for controlling the quantity of the medium passing through said nozzle, a second nozzle and coaxially arranged to said first nozzle and adapted to be displaced in the axial direction relatively to the former, the bore of the 30 second nozzle and the outer wall of the first nozzle forming together an annular channel the width of which can be adjusted by said displacement of said second nozzle and the 35 outer wall of said annular channel being so shaped that the medium passing through said channel flows in an oblique direction to the medium leaving the funnel shaped end of said first nozzle for causing an efficient 40 mixture of said mediums, a ring wall around said first mentioned nozzle and forming an annular channel with the latter that is a continuation of the afore mentioned annular channel, means to provide for a passage of 45 the medium from said annular channel to the bore of the first nozzle, means to admit to said annular channel a medium constituting an element of a combustible, and means to effect said displacement of the adjustable 50 nozzle and to regulate thereby the quantity of the respective mediums supplied to said annular channel.

2. A burner for gaseous and liquid fuels, in combination a nozzle with a bore that is 55 funnel shaped at one end adapted for the passage of a medium constituting an element of a combustible, a regulating device for controlling the quantity of the medium passing through said nozzle, a second nozzle coaxially arranged to said first nozzle and adapted to be displaced in the axial direction relatively to the former, the bore of the 60 second nozzle and the outer wall of the first

nozzle forming together an annular channel the width of which can be adjusted by said 65 displacement of said second nozzle and the outer wall of said annular channel being so shaped that the medium passing through said channel flows in an oblique direction to the medium leaving the funnel shaped end 70 of said first nozzle, for causing an efficient mixture of said mediums, a ring wall around said first mentioned nozzle and forming an annular channel with the latter that is a continuation of the afore-mentioned annular channel, means to admit to said annular channel a medium constituting an element of a combustible, a screw threaded spindle 75 fixed to the body of the first mentioned nozzle, an internally threaded member rotatable 80 on the spindle, an operative connection between the second nozzle and the rotatable threaded member, whereby a turning of said member causes a displacement of said second nozzle and thereby a regulation of the quantity of the respective mediums supplied to said annular channel.

3. A burner for gaseous and liquid fuels, having in combination a nozzle with a bore that is funnel-shaped at one end and adapted 90 for the passage of a medium constituting an element of a combustible, a regulating device for controlling the quantity of the medium passing through said nozzle, a second nozzle coaxially arranged to said first 95 nozzle and adapted to be displaced in the axial direction relatively to the former, the bore of the second nozzle and the outer wall of the first nozzle forming together an annular channel the width of which can be adjusted by said displacement of said second nozzle and the outer wall of said annular channel being so shaped that the medium passing through said channel flows in an oblique direction to the medium leaving the 100 funnel shaped end of said first nozzle for causing an efficient mixture of said mediums, a ring wall around said first mentioned nozzle and forming an annular channel with the latter that is a continuation of the afore 105 mentioned annular channel, means to provide for a passage of the medium from said annular channel to the bore of the first nozzle, means to admit to said annular channel a medium constituting an element of a combustible, means to effect said displacement of the adjustable 110 nozzle and to regulate thereby the quantity of the respective mediums supplied to said annular channel.

In testimony whereof I affix my signature.

HEINRICH NETTGENS.
